UNITED STATES PATENT OFFICE

2,507,418

COATING MACHINE FOR SHEETS
OF MATERIAL

Harry Whitney Osgood, Jr., and Alexander Jones,
Westbrook, Maine, assignors to S. D. Warren
Company, Boston, Mass., a corporation of
Massachusetts

Application September 30, 1946, Serial No. 700,278

4 Claims. (Cl. 91—33)

1

This invention relates to a coating machine and more particularly to a machine for coating separate sheets such as paper, cloth, asbestos, metal, plastic films and the like as distinguished from continuous webs. The machine to be described hereinafter and illustrated in the accompanying drawings was designed to coat relatively small sheets of about five inches width and fifteen inches length but it will be understood that the size of the sheets to be coated on a particular machine may vary and machines of different sizes may be provided. The machine is useful for instance for coating sheets of paper for test purposes, i. e. for test laboratory use and can be used for applying a variety of coating materials such as the conventional mineral coatings, wash coatings, emulsions, lacquers, etc.

The invention is illustrated in the accompanying drawings in which:

Fig. 1 is an elevation looking at the left hand side of the machine, the feed end being considered as being the rear end,

Fig. 1a is a rear view, partly in section of the arm 25, shaft 14, bushing 58 and latch 29 of Fig. 1,

Fig. 1b is a top plan view of one front corner of the stock table 2 of Fig. 1,

Fig. 2 is an elevation of the right hand side of the machine,

Fig. 3 is an elevation of the right hand end of the carrying or breast roll and the paper gripping mechanism,

Fig. 4 is a front view of the breast roll, and

Figs. 5, 6, 7 and 8 are right hand end views of the breast roll showing the gripping mechanism in different positions.

The apparatus consists generally of means for supporting and conveying a sheet to be coated in a predetermined path, means for applying mobile coating composition to the sheet as it moves in said path, an air doctor for spreading the coating on the sheet and for removing excess coating material therefrom as the sheet moves in said path and automatic means for actuating the coating applying means and the air brush.

The principal parts of the machine are the frame 1, the stock table 2, the breast roll 3 with its gripping mechanism, the coating applying mechanism 4 and the air doctor or air knife 5.

The stock table 2 is adjustably supported on the frame 1 by the hinge 6 and the adjustable rods 7. As appears in Fig. 1b, the front edge of the stock table is provided with adjustable stops 59 for stopping the forward movement of a sheet of paper to be picked up by the gripping

mechanism on the breast roll and notches 60 through which the gripping members 47 pass. The stock table is also provided with an adjustable guide plate 61.

5 The breast roll 3 is rotatably supported on the frame 1 by the shaft 8. It is rotated by the crank 9 through the shaft 10, cog wheel 11 and cog wheel 12. Obviously an electric motor or other suitable means may be substituted for the crank 9 for turning the shaft 10.

10 The coating applying mechanism comprises the pan 13 secured to and rotatable with the shaft 14, the color roll 15 rotatably mounted in the pan 13, the metering roll 16 also rotatably mounted in the pan 13. The bearings of the roll 16 are slidably mounted in the frame 17 and are adjustable by means of the screw 18 to vary the distance between the metering roll 16 and the color roll 15 and thus to vary the amount 15 of coating left on the color roll 15 for transfer to the sheet to be coated. Rolls 15 and 16 are rotated by the operation of the hand crank 9 operating through the cog wheels 11, 12, 19, 20 and 21, shaft 22, cog wheel 23 and cog wheel 24.

20 The color roll 15 is raised and lowered into and out of contact with the sheet to be coated carried upon the breast roll 3 by movement of the plunger 27 which is pushed forward by a piston in the cylinder 31 by air under high pressure supplied through pipe 32 from a source 35 under the control of valve 34 and cam 33 on the shaft 8. Plunger 27 engages the adjustable screw contact 26 on the arm 25. Arm 25 is rotatably mounted on the bushing 58 which is 30 keyed to the shaft 14. Movement of the arm 25 is transmitted to the shaft 14 by the latch 29, pivoted on the hub of the arm 25, engaging the notch 28 in the bushing 58. This construction permits the latch 29 to be disengaged

35 and the color pan assembly dropped for emptying and cleaning. The vernier 30, one scale of which is adjustably secured to the frame 1 and the other scale of which is secured to the bushing 58, may be used in setting the position of the color roll 15 with respect to the breast roll 3. Adjustment of the screw contact 26 and of the position to which the color roll 15 is raised takes care of different thicknesses of the sheets to be coated and to some extent regulates the amount 40 of coating applied to the sheet. Cam 33 is so shaped and positioned on the shaft 8 as to raise and lower the color roll 15 to apply coating to a sheet carried on the breast roll 3.

45 The air doctor 5 is of the type disclosed in U. S. Patent No. 2,139,628. It is adjustably

mounted on the shaft 36 supported by the upper end of the arm 37, the lower end of which is secured to the shaft 38. Shaft 38 also carries the arm 39, the movement of the free end of which is controlled by the adjustable stops 40 and 41. The air doctor may therefore be adjusted angularly about the axis of the shaft 36 and may be tilted to an adjusted position with its nozzle positioned to act upon the coating on a sheet carried on the breast roll 3 or tilted in the opposite direction to inoperative position.

The pan 42, supported on the frame 1 beneath the air doctor 5, serves to catch coating material blown off of the coated sheet by the air doctor 5.

The air doctor 5 is supplied, through pipe 45, with low pressure compressed air at measured intervals adjusted to act upon a coated sheet on the breast roll 3 from the source 62 through the air valve 63, which is operated by high pressure air supplied through valve 43, controlled by the cam 44 on the shaft 8.

The breast roll 3 includes the means for gripping and holding a sheet on the roll while coating is applied by the coating-applying mechanism 4 and smoothed by the air doctor 5 and then releasing the sheet. The roll 3 has a wedge-shaped portion (amounting to about one-fourth of the roll) removed, leaving about three-fourths of the roll surface with leading and trailing edges. The shaft 46 is rotatably mounted in the ends of the roll 3 adjacent said leading edge and carries a plurality (three illustrated) of gripping members 47 on the short arms 48 secured to the shaft. The surface of the roll 3 adjacent the leading edge is flattened to provide the surface 49 which cooperates with the gripping members 47. As shown in Figs. 5-8, the gripping members 47 are tilted or rotated from closed position, shown in Fig. 8 to open position, shown in Figs. 6 and 7 by means of the pin cam 50 secured to the end of the shaft 46. The cam 50 normally rests against the stop 51 and is pushed to its two rest positions shown in Figs. 6 and 8 by the spring 52. The spring 52 is supported on the plunger 53 which is pivotally connected at one end to the arm 54 secured to the shaft 46 and at the other end extends loosely through an opening in the arm 55 secured to the shaft 8. As the roll 3 rotates counter-clockwise as seen in Figs. 5 to 8 and as indicated by the arrows, the cam 50 first engages the pin 56 attached to the frame 1 as appears in Fig. 5 and is moved from its rest position shown in Fig. 8 to the position shown in Fig. 5. This movement opens the gripping member 47 from the closed or gripping position shown in Fig. 8 to the slightly opened position shown in Fig. 5. As the roll 3 continues to rotate, the cam 50 is tilted over to the full open position of the gripping members 47 as shown in Fig. 6. It then engages the pin 57 attached to the frame 1 as shown in Fig. 7 and is tilted to the closed position of the gripping members 47 as shown in Fig. 8.

The operation of the apparatus is as follows: Assuming that the breast roll is in the position illustrated in Fig. 6 with the grippers 47 in open position, that the plunger 27 is in retracted position and the color applying mechanism 4 is in lowered position (not shown) and that the air doctor 5 is in operative position as illustrated in Figs. 1 and 2, a sheet of paper or the like on the stock table 2 is pushed forward with its edge against the stops 59 where it can be engaged by the grippers 47 which are moved to closed or gripping position at this point (see Fig. 8) by op-

eration of the pin cam 50. The breast roll continues to move forward pulling the sheet with it and the color applying mechanism is raised to bring the color roll 15 into contact with the paper by the action of the cam 33. The application of coating to the sheet continues as the sheet moves forward so long as the cam 33 holds the color roll 15 in elevated position. The cam 33 may be set to stop the application of coating at or near the end of the sheet. Cam 44 is set to cause the air doctor 5 to act on the coated sheet to smooth the coating and remove excess coating and may be set to act on any length of sheet or any portion of the sheet. The breast roll continues to rotate after the sheet has been coated and the coating smoothed and arrives at the position shown in Fig. 5 where the grippers 47 are opened and the coated sheet released and is caught and removed by the operator.

In operation of the machine it may be desirable to stir the coating in the pan 13 before a coating operation is started or for some other reason to run the machine without applying coating. This can be done by simply shutting off the compressed air supply so that while the rolls are turned the coating roll remains out of contact with the breast roll.

We claim:

1. Apparatus for coating sheet material comprising a member having a sheet supporting surface adapted to be moved in a predetermined closed path, means carried by said member for gripping a sheet to be coated at one predetermined point in said path and for releasing said sheet at another predetermined point in said path, means positioned between said two points in said path for applying coating material to a sheet carried on said supporting surface, means between said two points in said path for smoothing coating on a sheet carried on said surface, means for automatically actuating said means for gripping and releasing the sheet to be coated and means for automatically moving said coating-applying means into coating applying position and for retracting said coating applying means after the movement of a predetermined portion of said surface past said coating-applying means.

2. Apparatus as defined in claim 1 in which the means for smoothing the coating on the sheet is an air doctor pivotally mounted independently of the coating applying means to be moved toward and away from said sheet supporting surface.

3. Apparatus for coating sheet material comprising a sector amounting to more than 180° of a cylinder mounted to revolve on its axis, means adjacent the leading edge of said sector for gripping and releasing the edge of a sheet to be coated, a pan for coating material, a color roll and a metering roll mounted to revolve in and move with said pan, said pan being mounted to pivot about a fixed axis from a position with the color roll in contact with said sector to a position with said color roll clear of said sector, an air doctor mounted to pivot about a fixed axis spaced apart from the axis of the pan from a position with the air doctor nozzle in contact with said sector to a position with said nozzle clear of said sector, means for rotating said sector and said color and metering rolls, means for periodically closing and opening said sheet gripping means, automatic means for periodically moving said pan about its axis to bring said color roll in

contact with said sector and return it to rest position and automatic means for periodically delivering air under pressure to said air doctor.

4. Apparatus as defined in claim 3 comprising cams mounted on the axle of said sector to turn therewith and means operated by said cams for moving the color pan about its axis and for admitting air under pressure to said air doctor.
